ELECTRIC SHAVING KIT

Howard F. Nenno, Rochester, N. Y.

Application February 28, 1946, Serial No. 650,765

11 Claims. (Cl. 240—2)

1

This invention relates to electric shaving kits and particularly to shaving kits of this kind adapted for travelers lodging in hotel rooms, where frequently there is no mirror sufficiently near a suitable electric outlet or suitable light may be wanting.

The principal object of the present invention is to provide a compact shaving kit or case in which mirror, light, and electric shaver may be conveniently carried.

Another object of this invention is to provide a kit of this kind which is light and which has suitable compartments for shaver and electric light, a mirror being mounted in the closure or lid which may be supported in a convenient position by a special hinge construction, whereby the closure is connected with the main or body part of the kit.

Another object of the invention is to provide a kit of this kind having a compartment for receiving an electric shaver of usual or preferred form, and another compartment for illuminating means enclosed in a translucent housing so that light may be transmitted therefrom upwardly and forwardly and to the shaver compartment.

Still another object of the invention is to provide a shaving kit having a compartment for an electric shaver, a compartment for an electric lamp, detachably mounted therein and enclosed in a translucent housing.

These and other desirable objects are accomplished by the construction disclosed as an illustrative embodiment of the invention in the following description and in the accompanying drawings forming a part hereof, in which:

Fig. 1 is a plan view of an open electric shaving kit illustrating one possible embodiment of the invention;

Fig. 2 is a plan view of the body part of the kit, the cover being removed;

Fig. 3 is a front elevation of the kit, the front wall being sectioned away to expose the interior;

Fig. 4 is an enlarged side elevation of the kit, the end wall being sectioned away to expose the interior;

Fig. 5 is a fragmentary section illustrating parts in another position; and

Fig. 6 is a diagram of the electric wiring.

The same reference numerals throughout the several views indicate the same parts.

Referring more particularly to the drawings, this invention comprises a case having a body 7 and a lid or closure 9 hinged thereto. As will be readily understood from the drawings, the body 7 and the cover 9 are each preferably formed of

2

molded plastic material. The body has a compartment 11 which may receive an electric shaver 13 and its usual extension cord 15. The electric shaver may be of any usual or preferred form and since it forms no part of the present invention, is not described in detail. A second compartment 17 is provided in the body, preferably adjacent its front wall, and may be enclosed in a housing 19 of substantially translucent material, such as 5 frosted glass, roughened or pigmented plastic, or the like, but which is preferably not strictly transparent so that the brightness of the filament of an electric bulb in the housing will not cause glare in the eyes of the user. The housing 19 forms the inner and top walls of the compartment and projects downwardly at the front as at 20 to a point adjacent the front wall of the body and forms an inclined or oblique vent opening therewith, as seen in Fig. 4, so air may circulate there-through but direct light rays from the bulb filament will not pass therethrough. A second vent opening 22 is formed in the housing and communicates with the compartment 11. These openings serve to ventilate the compartment 17. The top 10 wall of the housing 19 may project over the ends of the body to be secured thereto by means of screws 24 arranged in openings provided therefor in the side wall of the body. Mounted in the base of the compartment 17 is an electric conductor having an outlet 18 for the plug of the electric shaver, and a switch 21 controlled by a button 23. Connected with said electric conductor and mounted in the compartment 17 is an electric lamp 25 of usual or preferred form (conveniently an elongated bulb of the so-called "show case" type) having one end seated in an opening in a bracket 27, and its opposite end seated in a pair of opposing spring fingers 29 and 30. It will be noted that by this arrangement, the lamp is held in place securely but may be readily detached by disengaging it from the spring fingers for replacement with a new lamp. The lamp is connected with said electric conductor through one of said spring fingers 30 connected with the conductor 35 at 31 and a contact 33 which resiliently engages the end of the lamp.

Referring particularly to the diagram of the electric conductors, the plug 35 thereof (Fig. 1) may be connected with any available or suitable 40 source of energy. When the switch 21 is closed the current flows through 41 and 43 to the spring finger 30 and the lamp. The outlet 18 for the electric shaver is arranged between the conductors 37 and 41 and in parallel with the lamp. By this 45 arrangement it will be noted that the lamp 25 is

illuminated when the switch 21 is closed, independently of the operation of the electric shaver, and continues to be illuminated while the shaver is in operation.

The cover or lid 9 is connected to the body to swing thereon, from open to closed position, by means adapted to hold the lid resiliently in either open or closed position. To this end, one or more pairs of resilient hinge members are secured to the inside of the body by means of rivets 49 or other preferred means at a point near its bottom. Each pair of these hinge members projects above the body and comprises an inner blade or member 51 having an outwardly projecting stop 53 at its upper end, and an outer blade or member 55 having an inwardly projecting stop 57 at its upper end opposed to the stop 53. Mounted in the closure adjacent its rear edge is a blade or strap 61 adapted to be arranged between the opposing members 51 and 55 between which it may be resiliently engaged when the cover is in either open or closed position. When the lid is in its closed position, shown in Fig. 4, the blade 61 has one edge in engagement with the stop 57 on the outer member 55 and its other or opposite edge in engagement with the inner finger 51. It will be noted that the blade is at this time inclined downwardly and inwardly from the stop 57 so that it is resiliently engaged by the inner blade which presses it against the stop 57 and resiliently retains the lid in closed position. If the lid is opened the blade swings between the resilient members and slides on their inner surfaces flexing them apart against their resiliency until the blade engages the stop 53 on the member 51 and comes to rest in the position shown in Fig. 5 of the drawings. In this position of the parts, the lid is open and resiliently held in a position inclined upwardly and rearwardly from the rear wall of the body of the kit.

Secured in the inner face of the lid is a reflector or mirror 63 conveniently in position for use when the lid is open.

Since it is desirable to make the kit of light material to reduce its weight, its walls may be reinforced by means of the ribs 65, formed on the inner walls of the kit, which ribs closely embrace the side edges of the hinge members 51 and 55 and hold them against lateral or rotary displacement.

In use the kit is opened and the electrical extension 67 leading from the compartment 17 through an opening in its rear wall may be removed from the compartment 11 and its plug 35 connected with any suitable source of electric energy. The shaver may also be removed from the kit and connected with the outlet 18, although it may be permanently connected therewith. If the switch 21 is closed, the lamp will be lighted and the current will be supplied to the shaver, which will operate when the usual control switch on the shaver itself is closed. The kit may be supported on a table or stand so that the light from the compartment 17 is directed upwardly and forwardly therefrom to the face of the shaver before the mirror 63. Since the kit is light and compact, it can be held in one hand while operating the shaver with the other, if there is no convenient support therefor.

It is seen from the foregoing disclosure that a construction is provided which admirably fulfills the above-mentioned objects of the invention. It is to be understood that the foregoing disclosure is given by way of illustrative example

only, rather than by way of limitation, and that without departing from the invention, the construction may be varied within the scope of the appended claims.

5. What is claimed is:

1. An electric shaving kit comprising a body having a bottom and side walls and an open top, a cover member hinged to said body substantially at the rear edge thereof and adapted to be swung from a closed position closing the top of said body to an open position inclined upwardly and rearwardly from said rear edge of said body, a mirror mounted on the inner face of said cover member, a tubular incandescent electric light bulb mounted in said body close to the front edge thereof and extending approximately parallel to the front wall of the body, a light-diffusing translucent housing member extending substantially the full length of said front wall of the body and having a top wall over said bulb through which light may be transmitted upwardly and a rear wall lying to the rear of said bulb through which light may be transmitted rearwardly in a general direction toward said mirror when said cover member is open; said rear wall of said housing member being spaced substantially forwardly from the rear wall of said body to provide between them a compartment of substantial size for containing an electric razor, an electric outlet plug mounted in said body in position so that an electric razor may be plugged into it, and a flexible electric cord for supplying current to said outlet plug and to said bulb.

2. An electric shaving kit comprising a body having a bottom and integral side walls rising from the edges of the bottom, the front wall being of lesser height than the rear wall, a light-diffusing translucent housing member having a top wall, a deep rear wall, and a shallow front wall forming approximately an upward continuation of the low front wall of the body, said rear wall of said housing member being spaced materially forwardly from the rear wall of the body to provide between them a compartment for receiving an electric razor, an electric outlet plug mounted approximately flush with and below said rear wall of said housing member, an electric bulb mounted inside said translucent housing member, and a flexible electric cord connected to said outlet plug and to said bulb to supply electric current to them.

3. A construction as described in claim 2, in which said electric bulb is an elongated tubular incandescent bulb.

4. A construction as described in claim 3, further including a pair of spaced spring clip members within said translucent housing member near one end thereof for embracing and making electric contact with screw threads on the base of said bulb, a metal member resiliently engaging a central contact on the end of the base of said bulb, and a retaining member within said translucent housing member near the opposite end thereof, said retaining member having an aperture receiving the tip end of said bulb.

5. A construction as described in claim 2, in which the lower edge of said shallow front wall of said translucent housing member is spaced upwardly from the upper edge of said front wall of said body, to provide a ventilation slot through which heat may escape from the interior of said housing member.

6. A construction as described in claim 5, in which the lower edge of said front wall of said housing member and the upper edge of said front

wall of said body are each inclined obliquely upwardly and rearwardly to provide an oblique ventilation slot so that direct light rays from said bulb cannot pass through said slot.

7. An electric shaving kit comprising a body having a bottom and side walls formed integrally with the bottom and including a rear wall of full height, a front wall of lesser height, and end walls connecting the front and rear walls, each end wall being of full height for a portion of its length adjacent the rear wall and of lesser height for another portion of its length adjacent the front wall, a light-transmitting housing forming an electric bulb compartment in said body, said housing including a top wall, a rear wall depending from the rear edge of said top wall, and a shallow front wall depending from the front edge of said top wall in overlying relation to the front wall of said body, the ends of said housing resting on and being supported by the lesser height portions of the end walls of said body, an electric bulb within said housing, an electric outlet plug mounted in said body in such position that an electric razor may be plugged into said outlet plug and may be contained within said body when not in use, and a flexible electric cord operatively connected to said bulb and said outlet plug to connect them to a source of electric current.

8. An electric shaving kit comprising a body having a bottom and side walls formed integrally with the bottom and including a rear wall of full height, a front wall of lesser height, and end walls connecting the front and rear walls, each end wall being of full height for a portion of its length adjacent the rear wall and of lesser height for another portion of its length adjacent the front wall, a light-transmitting housing forming an electric bulb compartment in said body, said housing including a top wall, a rear wall depending from the rear edge of said top wall, and a shallow front wall depending from the front edge of said top wall in overlying relation to the front wall of said body, the ends of said housing resting on and being supported by the lesser height portions of the end walls of said body, screws passing downwardly through said housing and into said lesser height portions of said end walls to anchor said housing thereto, an electric bulb within said housing, an electric outlet plug mounted in said body in such position that an electric razor may be plugged into said outlet plug and may be contained within said body when not in use, and a flexible electric cord operatively connected to said bulb and said outlet plug to connect them to a source of electric current.

9. A construction as described in claim 8, further including thickening ribs formed integrally with said lesser height portions of said end walls of said body to strengthen said wall portions at the points where said screws extend into said portions.

10. An electric shaving kit comprising a body having a bottom and integral side walls rising from the edges of the bottom, the front wall being of lesser height than the rear wall, a light-diffusing translucent housing member having a top wall, a deep rear wall, and a shallow front wall forming approximately an upward continuation of the low front wall of the body, said rear wall of said housing member being spaced materially forwardly from the rear wall of the body to provide between them a compartment for receiving an electric razor, an electric outlet plug mounted approximately flush with and below said rear wall of said housing member, an electric bulb mounted inside said translucent housing member, a cover member hinged to said body substantially at the top of said rear wall thereof adapted to be swung from a closed position closing the top of said body to an open position inclined upwardly and rearwardly, a metal strip extending along the edge of said cover member adjacent said rear wall of the body throughout at least a portion of the length of said edge, said strip in cross section lying obliquely to the general plane of said cover member, a pair of resilient metal clip members mounted on said rear wall of said body and having at their upper edges lateral flanges faced inwardly toward each other, said strip on said cover member being received between said clip members below said lateral flanges, said clip members tending resiliently to move toward each other to act on said strip in such a way as to snap said cover member to a fully closed position wherein one edge of said strip is caught beneath one of said lateral flanges or to a fully open position wherein the opposite edge of said strip is caught beneath the other of said lateral flanges and said cover member is held firmly in said fully open position so that it will not jiggle or vibrate during a shaving operation, a mirror mounted on the inner face of said cover, and a flexible electric cord connected to said outlet plug and to said bulb to connect them to a source of electric current.

11. A construction as described in claim 10, further including ribs formed integrally on the rear wall of said body and embracing the lateral edges of said resilient metal clip members to hold them against lateral displacement relative to said rear wall of said body.
